ADAPTER HUB FOR A REEL OF RECORDING OR SIMILAR TAPE

Donald M. Eger, Elkhart, Ind., assignor to Crown
International, Inc., Elkhart, Ind.

Filed Jan. 2, 1975, Ser. No. 538,031

Term of patent 14 years

Int. Cl. D14—99

U.S. Cl. D26—1 R

Fig. 1

Fig. 2

Fig. 3

FIG. 1 is a perspective view of an adapter hub for a reel of recording or similar tape, showing my new design.

FIG. 2 is a side elevational view.

FIG. 3 is an end elevational view.

The rear of the adapter hub of my new design is unornamented.

I claim:

The ornamental design for an adapter hub for a reel of recording or similar tape, as shown and described.
